UNITED STATES PATENT OFFICE

JAMES L. KING AND ROBERT L. VANCIL, OF DARLINGTON, IDAHO; SAID KING
ASSIGNOR TO SAID VANCIL

SHEEP KNIFE

Application filed April 10, 1929. Serial No. 354,065.

This invention relates to an improved implement especially designed for docking and castrating lambs. It is a matter of common knowledge that at a certain age it is customary to "dock" (that is to cut off the tails) of lambs and to castrate the male species. For antiseptic reasons it has been found necessary to resort to repulsive methods in removing the testicles, and in some instances they are extracted with the human fingers.

The latter method was found objectionable because of infection resulting from the use of the fingers and under some methods it is quite unhealthy and undesirable to most persons in carrying out this work.

With this in mind we have evolved and produced a novel simplified instrument which permits the operator to carry on the docking and castration operation conveniently and with no loss of time.

In carrying out the invention we have constructed a form of instrument which comprises a handle, a knife, and a finger manipulated testicle grasping and pulling clamp, these features being arranged in intimate association to permit successive manipulation rapidly and with successful results.

In the drawings:

Figure 1 represents a perspective view of an instrument constructed in accordance with the present invention with the movable jaw of the clamp open.

Figure 2 is a side elevational view with the jaw closed.

As seen clearly in Figure 1, the reference numeral 3 designates a suitably shaped handle, one end of which is shaped as at 4 to provide a stationary grasping jaw. The working face or surface of this is provided with anti-slipping projections or teeth 5. Cooperable with the stationary jaw 4 is the movable jaw 6. This comprises a flat-like body having a lug 7 pivoted as at 8, in a slot formed in the inner end portion of the stationary jaw. This pivot is intermediate the ends of the movable jaw. The inner extending end is bevelled or cut off as at 9 and adapted to bear firmly against the adjacent surface of the handle when the jaw is in the open position seen in Figure 1. The free end

working surface of this jaw is provided with complementary anti-slipping teeth 5a. There is also a bevel at 10, against which the thumb of the operator is placed in moving the jaw 6 toward the jaw 4.

The reference characters 11 designate bifurcated arms between the furcations of which a sharpened blade or knife 12 is mounted. This knife has the double function of saving time in making the incision for removing the testicles and in docking or cutting off the tail.

When using the instrument for docking purposes, it is employed by grasping the handle 3 firmly and forcibly swinging the knife against the tail to cut it off at the point desired. The knife may also be employed for making an incision in the testicle casing, after which the clamping means may be brought into play for removing the testicles. This is done by placing the index finger beneath or around the stationary jaw 4, and forcing the thumb against the bevelled surface 10 to cause the jaws to grasp the testicle to conveniently extract it.

An instrument constructed in accordance with the present invention will be found especially useful in fulfilling the requirements of a device of this class in a sanitary and efficient manner. The simplicity is such as to make it unnecessary to enter into a more detailed description.

Minor changes in the shape, size, and rearrangement of details coming within the field of invention claimed may be resorted to, in actual practice, if desired.

We claim:

1. A sheep knife comprising a handle, a pair of longitudinally spaced right angularly extending arms carried by said handle and bifurcated at their free ends, a knife disposed in spaced parallelism with said handle and fastened between the furcations, one end of said handle being fashioned to provide a stationary clamping jaw, and a relatively movable jaw pivoted on said handle and cooperable with said stationary jaw.

2. A sheep knife comprising a handle, one end of which is fashioned to provide a stationary clamping jaw, the working surface

of said jaw being provided with an anti-slipping means, a relatively movable block like jaw pivoted between its ends on said handle at the inner end of said stationary jaw, said free end working surface of said movable jaw being provided with anti-slipping means and formed with a bevelled thumb surface.

3. A sheep knife comprising a handle, one end of which is fashioned to provide a stationary clamping jaw, the working surface of said jaw being provided with an anti-slipping means, a relatively movable block like jaw pivoted between its ends on said handle at the inner end of said stationary jaw, the outer end working surface of said movable jaw being provided with anti-slipping means and formed with a bevelled thumb surface, and the inner end of said movable jaw being bevelled for facilitating manipulation of the movable jaw.

In testimony whereof we affix our signatures.

ROBERT L. VANCIL.
